UNITED STATES PATENT OFFICE.

WILLIAM H. GEORGE, OF FAIRFIELD, IOWA, ASSIGNEE TO THE DEXTER COMPANY, OF FAIRFIELD, IOWA, A CORPORATION OF IOWA.

OPERATING-GEAR FOR WASHING-MACHINES.

1,253,023.

Specification of Letters Patent.

Patented Jan. 8, 1918.

Application filed February 5, 1917. Serial No. 146,646.

To all whom it may concern:

Be it known that I, WILLIAM H. GEORGE, a citizen of the United States, and a resident of Fairfield, in the county of Jefferson 5 and State of Iowa, have invented certain new and useful Improvements in Operating-Gears for Washing-Machines; and I do hereby declare that the following is a full, clear, and exact description thereof, reference being had to the accompanying drawings, and to the letters of reference marked thereon, which form a part of this specification.

This invention relates to improvements 15 in gearing primarily intended for actuating the operating shafts of power driven washing machines of the pounder type, and consists of the matters hereinafter described and more particularly pointed out in the 20 appended claims.

The gearing is shown herein as applied to what is known to the trade as a bench washer, and in the case of the particular machine illustrated, there are provided two 25 washing machines arranged side by side, with an upright drive shaft located between the tubs of the washing machines and connected to the operating shaft journaled in the lid of each tub. The connections between the drive shaft and operating 30 shafts are such that when the tub lid of either washing machine is raised, its driving connection with the operating shaft is broken. The advantages of my improved 35 gearing will appear as I proceed with my specification.

In the drawings:

Figure 1 is a top plan view of a bench washer provided with my improved gearing. 40 Fig. 2 is a transverse, vertical section through the same, in a plane indicated by the line 2-2 of Fig. 1.

Fig. 3 is a partial, transverse, vertical section through the same in a plane indicated 45 by the line 3-3 of Fig. 1.

Fig. 4 is a top plan view of a bearing plate forming a part of my improved gearing.

Referring now to that embodiment of my 50 invention illustrated in the accompanying

drawings:—10 indicates a bench adapted to support two washing machine tubs arranged side by side. At one side of said bench is located a hinged platform 11, which may be raised into the horizontal plane of the top 55 of the bench. Said platform is provided with folding legs 12, adapted to support it. 13, 13 indicate washing machine tubs of familiar construction, each having a lid 14 hinged along one edge in a manner soon to 60 appear, to a longitudinally extending board 15, forming the stationary top of both of said tubs. A transversely extending board or platform 16 is arranged between, and is attached to the two tubs of the washing 65 machine in the plane of the board 15 and tub lids 14, said board or platform 16 abutting at one end against the stationary top 15 of said tubs.

17 indicates a transversely extending 70 power shaft which is journaled in suitable bearings 18, 19, fixed to the longitudinal members of the bench 10, in a plane between the tubs 13, 13. 20 indicates a driving pulley fixed to the shaft 17 below the board 15, and 75 adapted to be driven from any suitable source of power.

21 indicates an upright shaft which is arranged in the plane of the shaft 17, and which is journaled at one end in an overhanging bearing sleeve 19^a made integral with the bearing 19. A bevel gear 21^a is fixed to the bottom end of said shaft which meshes with a bevel pinion 17^a on said shaft 17 (see Fig. 2). The top end of the shaft 21 85 projects through a bearing sleeve 22, in an elongated bearing plate 23 (see Fig. 4) fixed to and extending longitudinally of the stationary top or board 15. On the top end of said shaft above the bearing plate 23 is 90 fixed a spur gear 25. The gear 25 meshes with spur gears 26, 26, rotatively mounted on upright bearing studs 27, 27, carried by the bearing plate 23 near its ends.

A cover plate 28 incloses each of the gears 95 26, and each cover plate has ears 28^a through which bolts extend to secure them to the stationary top or board 15. A similar cover plate 29 incloses and protects the gear 25 on the upright shaft 21. Said cover plate 29 100

has ears 29^a which overlap one of each of the ears 28^a of the cover plates 28, and which are held in place by means of the same bolts that attach the said ears 28^a to the stationary 5 top 15. Each cover plate 28—28 also has an ear 28^b spaced above the board 16, adapted to be bolted to ears 29^b on the cover plate 29. It is apparent that said cover plates not only 10 protect the associated gears from being broken, but also prevent any liability of the person or clothing of the operator being caught in said gears.

Each cover plate 28 has a pair of transversely extending, spaced upright ears or 15 lugs 30, arranged in a plane above the tops of said cover plate on that side which overlaps the adjacent edge of the associated tub lid 14. These lugs are adapted to receive between them, a lug or ear 31 made integral 20 with a bearing bracket 32 fixed to each lid 14. As the bearing brackets 32 and associated parts, are the same in both instances, a description of one will suffice for both. The bearing bracket is arranged in a radial 25 line passing through the axis of the adjacent stud 27, and the axis of the tub lid to which it is attached. Said bracket 32 carries an upright stud 33 upon which a gear 34 is journaled, said gear meshing with the adjacent gear 26 on the bracket plate 23. The bearing bracket 32 also has a horizontally disposed bearing sleeve 35 arranged in a plane spaced above the gear 34 and in which a shaft 36 is journaled. Fixed to the outer 30 end or to that end of the shaft 36 adjacent to and above the gear 34, is a bevel gear 37 which meshes with an upwardly facing bevel gear 34^a made integral with the gear 34 before mentioned. A cover plate 38 fixed to 35 ears 32^a on the bearing bracket 32, incloses and protects the gears 34, 34^a and 37, respectively.

The inner end of the shaft 36 terminates 40 in a plane adjacent to the vertical axis of the associated tub, and to that end of said shaft is fixed a crank arm 39. This crank arm has a socket at its end in which is located a spherical member or ball 40 having a diametrically extending hole through it.

50 A horizontally disposed radial arm 41 fixed to an upright operating shaft 42, extends through the hole in the ball 40. The operating shaft 42 carries a pounder 42^a at that end within the tub, and said shaft is 55 capable of vertically reciprocating, alternating rotary movement in vertically spaced bearing sleeves made integral with a bearing bracket 43, fixed to the tub lid about the axis thereof.

60 A hinge member 50 is fixed to each end of the stationary top or board 15 which contacts with a hinge member 51 fixed to the adjacent edge of the associated tub lids 14. Said hinge members 50, 51 are connected by 65 pintles 52 which are in axial alinement with

the pintles of the hinges formed by the ears 30 on the cover plate 28 and the ears 31 of the bracket plates 32.

The operation of the mechanism thus far described, is as follows:—It is apparent that 70 the shaft 21 is driven in one direction through the gears 21^a and 17^a, from the power shaft 17. The gear 25 on the top end of the shaft 21 will, of course, drive or rotate the gears 26, 26, but in reverse directions. When the tub lids 14 are in their normally closed positions, the gears 34, which are in mesh with the gears 26, will, through the bevel gears 34^a and 37, respectively, operate to drive the shaft 36 in the 80 bearing sleeves 35 of the associated bearing bracket 32.

The crank arm 39 will, of course, rotate continuously in one direction, and this rotation is translated into a vertically reciprocating, alternating, rotary movement of the operating shaft 42 by means of the arm 41 and the ball 40 carried by the crank arm, in the manner well known.

When either of the tub lids 14 are swung 90 into an open position about the pintle of the hinge connection before described, the associated gear 34 will be disengaged from mesh with the associated gear 26, although said gear 26 still rotates by reason of its meshing with the gear 25. When the said tub lid is again closed, the gear 34 will again mesh with the associated gear 26 and movement is again imparted to the operating shaft 42. The parts are so proportioned and 95 so arranged that the gear 34 will not come into mesh properly with the associated gear 26, until the tub lid is almost closed, thus eliminating the operation of the operating shaft when the tub lid is in about a half-closed position and such danger as the operator is subjected to under such conditions.

In connection with the means for driving the washing machine operating shafts as before described, I provide a clothes wringing mechanism driven from the power shaft 17, which may, in its use, be swung about a vertical axis into any desired position. Means are also provided whereby the operating rolls of the clothes wringing mechanism may 110 be caused to rotate in one direction, may be stopped entirely, or may be caused to rotate in the opposite direction. Such means are 115 as follows:

60 indicates an upright shaft spaced from 120 the upright shaft 21, and arranged in the plane of the power shaft 17. The shaft 60 has bearing at its bottom end in a sleeve 18^a made integral with the bearing bracket 18 before mentioned. A bevel gear 61 is fixed to said bottom end of the shaft, which meshes with a bevel gear 17^b in the shaft 17. The top of the shaft 61 extends through the platform 16 and has bearing in an upright sleeve 62 having a radial flanged base 63

fixed to the top surface of the platform 16. That end of said shaft 61 above the bearing sleeve 62 is squared as at 64.

65 indicates a clothes wringer of the usual construction, normally located in the vertical plane of the shaft 17. Said wringer is rigidly fixed to a casing 65 which has a vertical bearing sleeve 66 normally bearing about the bearing sleeve 62. The bottom end 10 of the sleeve 66 terminates in a flanged base 66^a which bears upon the flanged base 63 of the bearing sleeve 62. The casing 65 has an apertured ear 68 to receive a removable pin 69 that is adapted to engage in suitable 15 holes 70 in the flanged base 63, to lock the casing against accidental horizontal swinging movement after it has been swung horizontally into the desired position.

The casing 65 provides bearing for one 20 end of the lower wringer roll shaft 71 and upon said shaft is loosely mounted oppositely facing bevel gears 72—73. Said gears are normally in mesh with a bevel gear 74 journaled in the sleeve 66, said gear having 25 a socket adapted to receive the squared end 64 of the shaft 60. A clutch collar 75 is keyed to the shaft 71 in a familiar manner, between the bevel gears 72 and 73, said collar being controlled in its endwise movement 30 on the shaft by means of a lever 76. Any convenient means is provided for locking the lever 76 in the desired position, such as, for example, the arcuate arm 77 fixed to the wringer frame above the casing 65.

35 It is apparent, from the foregoing description, that the wringer rolls may be stopped and started in either direction at the will of the operator, by the manipulation of the lever 76, and that the wringer may be operated and controlled at any position into which it may be swung.

40 My improved gearing is simple in construction and the parts thereof so coact with each other that they resist any tendency for 45 the tub lids to be distorted out of shape, thus insuring an easy and quiet running gearing especially adapted for washing machines.

I claim as my invention:

50 1. In a gearing of the kind described, in combination with a main support, a horizontal supplemental support hinged to said main support to swing about a horizontal axis, an upright operating shaft carried by 55 said supplemental support, a bearing plate fixed to said main support, an upright, continuously rotating driving shaft journaled at one end in said bearing plate, a gear on said upright shaft, a stud on said bearing plate, a gear mounted on said stud and meshing with the gear on said upright driving shaft, a bearing bracket fixed to said supplemental support, a horizontal shaft journaled in said bearing bracket, a gear on said 60 bearing bracket adapted to mesh with the gear on said stud, means operatively connecting the gear on said bearing bracket with the associated horizontal shaft, and means operatively connecting said horizontal shaft with said upright operating shaft. 70

2. In a gearing of the kind described, in combination with a main support, a horizontal, supplemental support hinged to said main support and adapted to swing about a horizontal axis, an upright operating shaft carried by 75 said supplemental support, a bearing plate fixed to said main support, an upright, continuously rotating driving shaft journaled at one end in said bearing plate, a gear on said upright driving shaft, a stud on said bearing plate, a gear on said stud and meshing with the gear on said upright driving shaft, a cover plate fixed to said main support and inclosing the gear on said stud, said cover plate having an ear, a bearing bracket fixed 80 to said supplemental support and having an ear hinged to said ear on said cover plate and forming a part of the hinged connection between said main support and said supplemental support, a horizontal shaft journaled in said bearing bracket, a gear on said bracket plate adapted to mesh with the gear on the stud on said bearing plate fixed to said main support, means operatively connecting the gear on said bearing bracket 85 with the associated horizontal shaft, means operatively connecting said horizontal shaft with the said upright operating shaft, and hinge members fixed to said main support and said supplemental support and forming 90 the other part of the hinged connection between said main support and said supplemental support. 95

3. In a gearing of the kind described, in combination with a main support, a supplemental support hinged to said main support to swing about a horizontal axis, an upright operating shaft carried by said supplemental support, a bearing plate fixed to said main support, an upright, continuously rotating, 100 driving shaft journaled at one end in said bearing plate, a gear on said upright driving shaft, a stud on said bearing plate, a gear on said stud and meshing with the gear on said upright driving shaft, cover plates 105 fixed to said main support and inclosing the gears on said upright driving shaft and on said stud, one of said cover plates having a pair of spaced ears, a bearing bracket fixed to said supplemental support and having an 110 ear engaged between and hinged to the spaced ears on said cover plate, a horizontal shaft journaled in said bearing bracket on said supplemental support, a bevel gear on said shaft, a stud on said bearing bracket, a combined spur and bevel gear mounted on said stud, the spur gear part of said combined gear meshing with the gear on the stud on said bearing plate fixed to said main support, the bevel gear part of said combined gear mesh- 115

1
ing with the bevel gear on said horizontal shaft, means connecting said horizontal shaft to the associated upright operating shaft, and hinge members fixed to said main support and supplemental support respectively, said ears and said hinge members providing the hinged connection between said main support and said supplemental support.

In testimony that I claim the foregoing 10 as my invention I affix my signature in the presence of two witnesses, this 20th day of December A. D. 1916.

WILLIAM H. GEORGE.
